UNITED STATES PATENT OFFICE.

OTTO SCHUTZ, OF NEW YORK, N. Y.

PNEUMATIC TIRE.

1,216,851.

Specification of Letters Patent. Patented Feb. 20, 1917.

Application filed October 6, 1914. Serial No. 865,268.

To all whom it may concern:

Be it known that I, OTTO SCHUTZ, a citizen of the United States, residing at New York, county of New York, State of New York, have invented new and useful Improvements in Pneumatic Tires, of which the following is a specification.

This invention relates to a pneumatic tire in which the outer tubular casing or shoe 10 is provided with a plurality of partitions or diaphragms to divide the casing into a plurality of annular chambers. In each chamber is arranged a thin elastic pneumatic tube, and each tube is provided with 15 means for simultaneously inflating the tubes.

The invention is essentially designed to prevent entire flattening or collapse of the tubular casing when one or more of the inner tubes get punctured. When punctured any of the inner pneumatic tubes can readily be removed from the outer casing, in order to repair the tube without displacement of the other tubes. Each tube is provided with a separate air inlet tube so 25 that when any of the tubes are punctured that particular air tube can be removed from the casing with its air inlet.

The novel features of the invention are more fully described in the following specification and claim and illustrated in the accompanying drawing in which:

Figure 1 represents a vertical transverse section of a tire embodying this invention.

Fig. 2 is a side elevation of the air inlet 35 tubes.

Fig. 3 is a vertical section of one of the air inlet tubes.

Fig. 4 is a horizontal section taken along the line $x-x$ of Fig. 2.

40 In this drawing the letter a designates a rim which is of the ordinary clincher type of wheel and adapted for use with a motor vehicle or bicycle. An outer slotted tubular casing b is normally clenched to the rim as is well known.

This casing is provided with a pair of partitions or annular diaphragms c projecting from the inner portion of the tread toward the rim portion of the casing. These partitions divide the inner portion of the casing into three chambers d , each being open adjacent to the rim to give access to a chamber. A pneumatic elastic tube e is arranged in each chamber, and secured to each tube is 50 an air inlet tube f extending through the slotted casing and a hole in the rim of the

wheel. Each inlet tube represents a separate medium communicating with an air tube for pumping air into all the pneumatic elastic tubes. Each air tube is circumferentially 60 screw threaded as shown at g and the inner faces of the tubes are angular as indicated in Fig. 4, in order to bunch the segmental tubes together to form a complete circle. The outer ends of the tubes can be covered 65 by means of a screw cap h to prevent dirt from entering or leakage of the air, and the end of each tube may also be separately covered with a screw cap.

The lower portion of the tubes are locked 70 together and held in position relative to the rim by means of a threaded sleeve i having a flange j for engagement with the inner slotted portion of the outer casing. A nut k is adapted to lock the sleeve to the rim of 75 the wheel. The threaded stems of the air tubes where they emerge from the rim are engaged by a nut m for alining and preventing centrifugal thrust of the tubes.

Any form of spring air inlet valve may 80 be mounted in the bore of each tube to prevent the air from escaping from the tube. The air tubes are all simultaneously inflated from a single pump so that the pressure in one air tube will equal the pressure in the other, thus giving uniform resistance to the sides as well as the tread of the tire. They may be inflated separately when desirable. The air tubes when clustered and locked together constitute practically 85 a single inlet tube, thereby facilitating the connection of a coupling when inflating the tire.

The partitions c are each attached at one edge to the inner side of the tread portion 90 of the casing b . Their other edges are free and spaced from the inner side of the rim portion of the casing b , to render them laterally flexible. The lateral flexibility of the partitions c permits the air pressure in 100 the tubes e to be evenly distributed throughout the interior of the casing b , and when one or two of the tubes e are punctured permits the other tube or tubes to expand and fill up the casing. The fact that the free edges of the partitions are spaced from the inner side of the rim portion of the casing b , permits the tubes e to be readily and quickly placed within and removed from the chambers d , and prevents any strain 105 from being thrown on the connections between the tubes e and the air inlet tubes f .

It is to be noted that the tubes *e* project beyond the free edges of the partitions *c* and that the air inlet tubes *f* are located between the free edges and the inner side of the rim portion of the casing *b*.

Sometimes it is desirable when one of the pneumatic tubes is punctured to increase the pressure in the other tubes. This function can be accomplished by capping one of 10 the air inlet tubes and increasing the pressure in the other air tubes.

I claim:

A pneumatic tire comprising a tubular slitted casing, a pair of relatively spaced 15 annular partitions located within the casing and each attached at one edge to the inner side of the tread portion of the casing, said partitions being inclined in the direction of each other and extending from the tread 20 portion in the direction of the rim portion

of the casing and having their other edges free and spaced from the inner side of said rim portion, said partitions dividing the casing into three chambers, a tube located in each chamber and extending beyond the 25 free edges of the partitions, and means to permit the tubes to be inflated, said means being connected to the tubes at a point in spaced relation to the free edges of the partitions, so as to prevent injuring said means by the partitions on the compression of the tube.

In testimony whereof I have hereunto set my hand in the presence of two subscribing witnesses.

OTTO SCHUTZ.
